United States Patent Office

Des. 216,977
Patented Mar. 24, 1970

216,977

PUMP

John H. Collamore, Jr., West Barrington, R.I., assignor to Dart Union Company, a corporation of Rhode Island

Filed Apr. 25, 1969, Ser. No. 16,903

Term of patent 14 years

Int. Cl. D23—01; D15—02
U.S. Cl. D23—14

FIG. 1

FIG. 2

FIG. 1 is a side elevational view of a pump showing my new design;

FIG. 2 is an end view taken from the left-hand side of FIG. 1;

FIG. 3 is an end view taken from the right-hand side of FIG. 1;

FIG. 4 is a top view thereof; and

FIG. 5 is a bottom view thereof.

The undisclosed side is substantially the same in appearance as the side disclosed in FIG. 1.

I claim:

The ornamental design for a pump, substantially as shown and described.
